COMBINATION CONTAINER AND DISPLAY UNIT

Elliott Nonas, New York, N. Y.

Application August 6, 1949, Serial No. 4,335

Term of patent 14 years

(Cl. D58—12.6)

To all whom it may concern:

Be it known that I, Elliott Nonas, a citizen of the United States and a resident of the city, county, and State of New York, have invented a new, original, and ornamental Design for a Combination Container and Display Unit, of which the following is a specification, reference being had to the accompanying drawings, forming a part hereof, in which:

Fig. 1 is a perspective view of a combination container and display unit showing my new design, the unit being shown in closed position;

Fig. 2 is a perspective view thereof, showing the unit in fully open position; and

Fig. 3 is a perspective view showing the unit in partly open position.

I claim:

The ornamental design for a combination container and display unit, as shown.

ELLIOTT NONAS.
